Primary Examiner — Lakiya Rogers*Assistant Examiner* — Altaira Swangin(74) *Attorney, Agent, or Firm* — Theodore Heske, III(57) **CLAIM**

The ornamental design for a round light emitting display, as shown and described.

DESCRIPTION

FIG. 1 is a perspective view of a round light emitting display showing our new design;

FIG. 2 is a front elevation view thereof;

FIG. 3 is a back elevation view thereof;

FIG. 4A is a right elevation view thereof, enlarged partial views FIG. 4B and FIG. 4C being defined by dot-dashed lines;

FIG. 5A is a left elevation view thereof, enlarged partial views FIG. 5B and FIG. 5C being defined by dot-dashed lines;

FIG. 6 is a top plan view thereof; and,

FIG. 7 is a bottom plan view thereof.

Any broken lines in FIG. 1 through FIG. 7 are unclaimed portions of the design. The dot-dash lines visible in FIGS. 4A, 4B, 4C, 5A, 5B, and 5C indicate partial views and form no part of the claimed design.
